UNITED STATES PATENT OFFICE

158,250

BATH BRUSH

Eric Leopold Hugo Cosby, Jr., London, England

Application July 18, 1947, Serial No. 140,355
In Great Britain May 9, 1944

Section 1, Public Law 690, August 8, 1946

Term of patent 14 years

(Cl. D9--2)

To all whom it may concern:

Be it known that I, Eric Leopold Hugo Cosby, Jr., a subject of the King of Great Britain, residing at London, England, have invented a new, original, and ornamental Design for a Bath Brush, of which the following is a specification, reference being had to the accompanying drawings, forming a part thereof.

I claim:

The ornamental design for a bath brush, as shown.

ERIC LEOPOLD HUGO COSBY, JR.
